UNITED STATES PATENT OFFICE.

WILLIAM B. GARRISON, OF WASHINGTON, DISTRICT OF COLUMBIA.

DESIGN FOR A TRAY OR PLATE.

43,300.

Specification for Design.

Patented Dec. 3, 1912.

Application filed June 7, 1912. Serial No. 702,342. Term of patent 7 years.

To all whom it may concern:

Be it known that I, WILLIAM B. GARRISON, a citizen of the United States, residing at Washington, in the District of Columbia, (whose post-office address is No. 1225 Pennsylvania avenue northwest, in said city,) have invented a new, original, and ornamental Design for a Tray or Plate, of which the following is a specification, reference being had to the accompanying drawing, forming part thereof.

The figure is a face view of a tray or plate, showing my new design.

I claim:

The ornamental design for a tray or plate, as shown.

WILLIAM B. GARRISON.

Witnesses:

E. EDMONSTON, Jr.,
E. A. WAKEFIELD.
